UNITED STATES PATENT OFFICE.

JAMES HAROLD FORD, OF BALTIMORE, MARYLAND.

ADDRESSING-MACHINE.

1,241,946.

Specification of Letters Patent.

Patented Oct. 2, 1917.

Application filed December 2, 1916. Serial No. 134,651.

To all whom it may concern:

Be it known that I, JAMES HAROLD FORD, a citizen of the United States, residing at Baltimore, in the county of Baltimore City and State of Maryland, have invented new and useful Improvements in Addressing Machines, of which the following is a specification.

This invention relates to improvements in machines for printing addresses on packages and the like, and has particular application to a portable addressing machine.

In carrying out the present invention, it is my purpose to provide a portable addressing machine, which may be handled conveniently, and whereby names and addresses may be printed on packages and the like.

It is also my purpose to provide a machine of the class described, which will be self-inking, thereby insuring a proper inking of the type, and the proper operation of the machine.

With the above and other objects in view, the invention consists in the construction, combination, and arrangement of parts hereinafter set forth and falling within the scope of the claims.

In the accompanying drawings:—

Figure 1 is a top plan view of an addressing machine constructed in accordance with the present invention.

Fig. 2 is a view in elevation of the same.

Fig. 3 is a cross sectional view on the line 3—3 of Fig. 1.

Fig. 4 is a cross sectional view on the line 4—4 of Fig. 1.

Referring now to the drawing in detail, 1 designates a base constructed of any suitable material and of any desired weight, 40 and having the upper side equipped with a handle 2. Slidably mounted within a transverse bore formed in the base 1 adjacent to the bottom edge thereof is a rod 3 arranged centrally of the ends of the base 1, 45 and secured to one end of the rod 3 is a horizontal guide rail 4, while upstanding from the rod 3 adjacent to the respective ends thereof are stop pins 3' adapted to engage the front and rear edges of the base to limit 50 the sliding movement of the rod. The rod 3 is adapted to be held in either one of two positions, and the upper edge thereof is formed with notches 3" spaced apart and adapted to move into and out of alinement 55 with a vertical bore 3" formed in the base 1 and opening onto the bottom of the base.

Mounted within the bore 3" is a spring pressed dog 3" designed to engage in the corresponding notch 3" to hold the rod 3 in the desired adjusted position. 5 designates 60 a carriage embodying a strip 6 formed with a series of openings 7 spaced apart longitudinally of the strip and a series of openings 7' lying parallel with the openings 7. Slidably mounted within each opening is a 65 plunger rod 8, having the lower end equipped with a type block 9, and the upper end with a key 10, having the letter inscribed thereon corresponding to the type. One side of the strip 6 is equipped with an 70 outwardly projecting handle 11, while secured to the other side is a guide rail 12, that lies parallel with the guide rail 4, and is connected thereto by means of interconnected rollers 13, that serve to permit the 75 carriage to be shifted longitudinally of the base. Surrounding each plunger rod 8 is a coiled expansion spring 14 that acts to hold the type blocks normally elevated. Mounted within a recess in the base 1 below the 80 plane of the type is an inking roller 15, capable of movement out of such recess to engage the type blocks as the carriage is shifted from one position to another relatively to the base. Thus the type is inked. 85 The type blocks mounted upon the plungers in the openings 7' carry the figures, while the type blocks on the plungers in the openings 7 carry the letters.

In practice, the base 1 is placed upon the 90 package or other article to be printed upon, and the carriage shifted from one position to another to bring the type blocks into the proper position for printing, and as each type block is brought into position, it is 95 pressed downwardly against the action of the spring 14. Upon the releasing of the key, the spring restores the type block to normal position so that the carriage may be shifted to bring the next desired type block 100 into position. When it is desired to print letters and figures in the same line, the carriage may be pulled away from the base 1 to bring the type carrying blocks into printing position, and in this movement of the 105 carriage the rod 3 moves transversely of the base 1 and the dog 3" engages in the corresponding notch 3" to hold the carriage in such position.

While I have herein shown and described 110 the preferred form of my invention by way of illustration, I wish it to be understood

that I do not limit or confine myself to the precise details of construction herein described and delineated as modification and variation may be made within the scope of the claims and without departing from the spirit of the invention.

I claim:

1. A machine of the class described, comprising a base, a guide rail secured to one side of the base and offset therefrom, a carriage, a guide rail secured to said carriage in a line parallel with the first named guide rail, interconnecting rollers connecting said guide rails, whereby said carriage may be shifted longitudinally of the said base, and type blocks carried by said carriage and movable to printing and non-printing positions.
2. A machine of the class described, comprising a base, a guide rail secured to one side of the base and offset therefrom, a carriage, a guide rail secured to said carriage in a line parallel with the first named guide rail, interconnecting rollers connecting said guide rails, whereby said carriage may be

shifted longitudinally of the said base, type blocks carried by said carriage and movable to printing and non-printing positions, plungers carrying said type blocks respectively, and keys upon the upper ends of the said plungers bearing characters corresponding to the type blocks.

3. A machine of the class described, comprising a base, a guide rail secured to one side of the base and offset therefrom, a carriage, a guide rail secured to said carriage in a line parallel with the first named guide rail, interconnecting rollers connecting said guide rails, whereby said carriage may be shifted longitudinally of the said base, type blocks carried by said carriage and movable to printing and non-printing positions, plungers carrying said type blocks, respectively, keys upon the upper ends of the said plungers bearing characters corresponding to the type blocks, and a spring surrounding said plungers for holding the type blocks normally in non-printing position.

In testimony whereof I affix my signature.

JAMES HAROLD FORD.
